UNITED STATES PATENT OFFICE

155,440

DESIGN FOR A PERCOLATOR KNOB

Peter Muller-Munk, Pittsburgh, Pa., assignor to
 Ekco Products Company, Chicago, Ill., a corporation of Illinois

Application April 20, 1948, Serial No. 145,846

Term of patent 7 years

(Cl. D44—26)

To all whom it may concern:

Be it known that I, Peter Muller-Munk, a citizen of the United States, residing at Pittsburgh, county of Allegheny, State of Pennsylvania, have invented a new, original, and ornamental Design for a Percolator Knob, of which the following is a specification, reference being had to the accompanying drawing forming part thereof.

Fig. 1 is a side elevational view of a percolator knob, showing my new design.

Fig. 2 is a top plan view.

Fig. 3 is a bottom plan view.

Fig. 4 is a vertical sectional view on line 4—4 of Fig. 2.

I claim:

The ornamental design for a percolator knob, as shown.

PETER MULLER-MUNK.
